UNITED STATES PATENT OFFICE.

CHARLES SUMNER EVANS, OF BERKELEY, CALIFORNIA.

PUZZLE.

1,356,703.

Specification of Letters Patent. Patented Oct. 26, 1920.

Application filed May 14, 1918. Serial No. 234,375.

To all whom it may concern:

Be it known that I, CHARLES SUMNER EVANS, a citizen of the United States, and a resident of Berkeley, county of Alameda, 5 and State of California, have invented a new and useful Puzzle, of which the following is a specification.

My invention relates to puzzles, and an object of the invention is to provide an 10 amusement device of current interest.

Another object of the invention is to provide a test for the steadiness of hand and the patience of the user.

The invention possesses other features of 15 advantage, some of which, with the foregoing, will be set forth in the following description of the preferred form of my invention which is illustrated in the drawings accompanying and forming part of the 20 specification. It is to be understood that I do not limit myself to the showing made by the said drawings and description, as I may adopt variations of the preferred form within the scope of my invention as set forth 25 in the claims.

Referring to the drawings, Figure 1 is a plan view of the puzzle of my invention before solution.

Fig. 2 is a plan view of the puzzle after 30 solution.

Fig. 3 is a plan view of a portion of the puzzle.

Fig. 4 is a vertical sectional view taken 35 on the line 4-4 of Fig. 3.

Fig. 5 is a vertical sectional view taken on the line 5-5 of Fig. 1.

Broadly considered my puzzle consists of two pictures one adapted to be positioned upon the other. The lower or fixed picture 40 expresses a certain set of facts or state of mind in opposition to or different from the upper one. Mechanical means difficult to control are provided for moving the loose or mobile upper picture into position or into 45 register with the lower one, and the task consists in manipulating the mobile operative means to effect such movement, so that the meaning of the lower picture is altered by the elements orderly superposed upon it.

The present embodiment of my invention 50 includes a shallow case 6 having a transparent cover or top 7 tightly sealed thereon, so that access to the interior of the case is denied, but the interior is open to view. A 55 picture 8 preferably of a well known but unfavorably regarded monarch is affixed to the

flat bottom 9 of the box. The face preferably expresses a satisfying self-esteem.

Arranged in the box and movable about therein are one or more thin sheets of card- 60 board or other appropriate light material, shaped and printed to simulate separate features of the face of the individual pictured. In the present instance a piece of card 11 roughly of T-form as shown in Fig. 3 is 65 shaped and printed to present the appearance of two badly blackened eyes, one 12 being fully closed and the other 13 being nearly closed. A molded nose 14, preferably of cork or papier-mâché, and formed and 70 colored to simulate the effects of hard usage is attached to the T-form card so that the nose and eyes are movable, together as one member. Such member if desired may be molded all in one piece from papier-mâché 75 or other suitable light material, but however made, it is intended to represent the eyes and nose of the personage delineated in the picture 8, as they would appear after a disastrous personal encounter. The bottom of 80 the nose and eyes member may be left flat, but preferably a slight hump 16 is provided either by a small object placed between the card 11 and the bottom of the nose, or other appropriate means, at a point to one side of 85 or on the median line of the nose and somewhat nearer to the eyes than the tip of the nose. The purpose of this hump is to make the movement of the nose and eyes member uncertain and difficult to control because it 90 serves as a pivot about which the member readily turns. A drop of mercury or a bearing ball 17 is provided in the casing with which to move the nose and eyes member by 95 appropriate tipping of the case.

The existence of the hump 16 makes it almost impossible to move the nose and eyes member bodily sidewise, the tendency being for it to swing about the hump as a pivot. In order to make the movement of the member 100 possible the tip of the nose member is undercut as at 18. This forms a sort of shallow socket not apparent at first view but by means of which the mercury drop or ball 17 may be made to exert slight lateral pressure upon the member. Preferably a similar hold is provided at the opposite end by a hollow 19.

The task or puzzle consists in moving the nose and eyes member with the mercury 110 drop or ball 17, by tipping the case, so as to superpose the member upon the picture 8,

thus changing the expression of self-esteem thereon to one of mournful memories.

It will be found that a nose and eye member constructed in accordance with the above 5 description can be moved about the case by careful manipulation of the mercury drop or ball at either end of the nose. Contact with the side of the nose merely swings the member about a vertical axis. At best the course 10 of the member is erratic. Of course the task is much simplified by making the under surface of the member flat, and this may be done if desired.

If preferred, the superposable member 15 may consist of one or both eyes, or of eyes and nose separately, or other, or all features separately or together. In each case the superposed parts suggest an idea or tell a story different from, or contrasted with, the 20 idea or story expressed by the uncovered picture or face.

If desired a small square block 21 of felt or cork may be included in the case. This 25 block is to be interposed between the mercury drop or ball and the mobile nose and eye member in certain positions when it is desired to exert pressure against the eye members only. The eye members are quite thin, and the mercury or ball runs over them 30 without affecting their position. The block presents a larger surface to the mercury or ball and so may be maneuvered into position against the thin edge of the eye member and the latter moved meditately instead of directly. Where the mobile member or 35 feature is entirely flat without a molded portion, it is preferred to make it quite thin and use the weight operated block 21 for effecting all movements thereof.

40 I claim:

1. A puzzle comprising a case, a picture arranged in said case, a mobile member adapted to be superposed upon said picture to alter the expression or meaning thereof, 45 and gravity operated means for moving said mobile member.

2. A puzzle comprising a case, a picture arranged in said case, a mobile member adapted to be superposed upon said picture to alter the meaning thereof, gravity operated means for moving said member and means for increasing the difficulty of moving said member in any given direction.

3. A puzzle comprising a case, a picture 50 arranged in said case, a mobile member adapted to be superposed upon said picture

to alter the meaning thereof, means for moving said member and means for tending to cause said member to turn about an axis when subjected to said moving means. 60

4. A puzzle comprising a case, a picture arranged in said case, a mobile member adapted to be superposed upon said picture to alter the meaning thereof, mobile means for moving said member about said case, 65 and means for permitting said moving means to exert lateral pressure against the end of said mobile member.

5. A puzzle comprising a case, a picture arranged in said case, a mobile member 70 adapted to be superposed upon said picture to alter the meaning thereof, mobile means for moving said member about said case, means for permitting said moving means to exert lateral pressure against the end of said 75 mobile member, and means tending to cause said member to turn about an axis when subjected to said moving means.

6. A puzzle comprising a case, a pictured face arranged in said case, a mobile member 80 consisting of a molded or pictured feature or features adapted to be superposed upon said pictured face to alter its expression, and mobile means for moving said member.

7. A puzzle comprising a case, a pictured face arranged in said case, a mobile member consisting of a molded nose adapted to be superposed upon said picture to alter its expression, and mobile means for moving said member, said member being provided with a shallow recess for rendering more effective the engagement of said moving means with 90 said member.

8. A puzzle comprising a pictured face, a 95 mobile member consisting of a molded or pictured feature adapted to be superposed upon said pictured face to alter its expression and provided with a hump upon its under surface, and means for moving said 100 member.

9. A puzzle comprising a case, a picture arranged in said case, a mobile member adapted to be superposed upon said picture to alter the meaning thereof, means for 105 moving said member, and a block adapted to be interposed between said member and said moving means.

In testimony whereof, I have hereunto set my hand at San Francisco, California, 110 this 8th day of May, 1918.

CHARLES SUMNER EVANS.
